UNITED STATES PATENT OFFICE

GEORGE C. SOULE AND JOHN B. WOODBURY, OF SOUTH PORTLAND, MAINE, ASSIGNEES
TO MAINE STEEL PRODUCTS COMPANY, OF PORTLAND, MAINE, A CORPORATION OF
MAINE

SNOWPLOW NOSE AND CUTTER BAR THEREFOR

Application filed October 18, 1929. Serial No. 400,545.

This invention relates to snow plows and particularly to nose constructions for the same. Some plows have been heretofore made in two principal types, one with a steep sided nose, and the other with noses whose lower edges met the ground with a gently sloping angle. These types were expected to meet all conditions, but while each type has been generally satisfactory for certain conditions, each has failed to meet certain other conditions for which it proved to be ill adapted.

The two more usual and more contradictory conditions are first where deep heavy drifts have been formed which require great power to push the plow through. On these the steep sided plow does not push through as easily as the plow whose lower edge meets the ground at a gentle angle.

The second condition exists where there is hard packed or trodden snow on which all plows have had a tendency to ride up, thus leaving unremoved snow on the road. On this type of work the steep sided plow has generally done better work because its steep angles of incidence to the road surface creates what is commonly called suction and tends to dig down and remove the hard snow close to the ground. This plow, however, due to the steepness of its sides is pushed through deep heavy snows only with great difficulty and tends to bounce back from hard packed drifts.

The object of this invention is to produce a plow which will meet both of these conditions efficiently while otherwise fulfilling the general requirements of a plow nose. It provides a type of nose which holds the plow down without holding it back. It provides a plow capable of being pushed through heavy drifts without loss of efficiency due to high resistance and in avoiding the riding up tendency above described leaves a road which is properly cleaned and which has a surface affording a maximum of traction for the motor equipment which pushes the plow. This is very important because a layer of snow left on a road surface seriously reduces the tractive power, especially in the case of plows mounted on trucks, as the traction area in

that case is somewhat limited and trucks tend to dig in and lose traction if too much snow is left on the road.

Our present invention contemplates a plow nose having this general lifting and rolling function present in the construction and design of its mold boards, but also provided with a cutter bar which is normally cooperative with the general curvature of the mold board to provide for the lifting of the snow, and has a downwardly disposed edge adapted to counteract the tendency of the cutter bar to lift and ride in snows that are compacted on the road surface. These together with various other features constitute the inventions involved in our present application. As illustrative thereof we have shown in the accompanying drawing an embodiment which illustrates the principles involved and at the same time indicates a structure which is well adapted to practical use and capable of embodiment in snow plow construction of very high efficiency and capable of manufacture at reasonable cost. In the drawing:

Fig. 1 is a front elevation of a plow nose in accordance with our invention.

Fig. 2 is a bottom view of the same.

Fig. 3 is a sectional view through the nose and cutter bar, and

Fig. 4 is an enlarged section of the cutter bar.

In the form shown our snow plow nose consists of a pair of side mold boards 1 which are welded together at a common joint 2. These mold boards 1 which are concaved and disposed in a V or wedge shape, are supported back of their weld line 2 by transverse webs 3 which are also preferably welded to the mold plates and constitute a bulk head which braces the forward end of the plow. At their lower edges the mold plates 1 carry cutter bars 5 having a main surface 5² disposed at as low an angle to the ground as possible, while still leaving room enough under it for reinforcements sufficiently strong to enable it to withstand the shocks and strains to which it is subjected. The object of this low angle is to convert a fixed and given amount of push available from the motive equipment into the greatest possible

lifting power on the general principle of a wedge. The more slender the wedge the greater the lifting power for any given push.

For such a construction as is herein shown, 5 an angle of substantially 25° has been found practical but still lower angles may be found possible provided adequate support is made available which can be located beneath so low an angle.

10 The bar 5 in advance of its general surface 5² is pitched down at an angle of approximately 20° and its edge still further carried down by a bevel 5¹ at an angle of approximately 20° , so that the sum of the bend and 15 the bevel amount to about 40° . This converts the low angle of the upper portion of the cutter bar 5² into a sharp angle of incidence with the ground of approximately 65° so that the cutter bar is in reality concaved 20 reversely to the curvature of the mold boards.

25 1. The upper portion of these mold boards may be variously curved or concaved according to the particular kind of work that they are to do and whether for truck or tractor use. In the present nose, however, they merge at a low angle into the cutter bar region so as to form with it a substantially continuous wedging surface of low angularity as before described.

30 Referring now to the formation of this edge portion of the nose of the plow, it will be noted that we provide a reinforcing bar 6 which underlies the cutter bar 5 preferably including the plate 1 which constitutes the 35 mold board of the nose.

At the rear of this edge area we provide angle beams 7 which act as general frame pieces for the nose construction. The two pieces 7 are brought together in the line of 40 the apex of the V and are suitably welded.

45 These angle pieces 7 are connected by fitted web members 8 welded to the pieces 7 and also to the mold member 1 and to the reinforcing bar 6. These constitute a box construction on each side of the nose which is closed in by a plate 9 which is welded at one edge to the angle beams 7 and its other edge to the reinforcing bar 6 and at the same time spans the webs 8 to which it is welded to form 50 a unitary structure.

55 The weld of the two plates 1 at the portion 2 constitutes a vertical V-shaped structure and this is reinforced by the transverse plate 3 which provides a pyramidal member affording great strength to the nose of the plow. This structure is reinforced by a cross beam 10 which backs up the aforementioned structure by web members 11 welded thereto.

60 The cross member 10 is part of the main frame of the nose member of the plow and is in turn supported by other frame members not necessary to be considered herein.

65 It will be seen by reference to these figures that we have provided a nose member which provides mold plates which may have the de-

sired conformation for easily penetrating deep heavy snow after the principle of the slender wedge. These mold plates, however, are formed with a box edge of great strength and firmly braced by the nose bulk heads and afford a most efficient mounting for the cutter bars 5.

70 By our cutter bar construction we provide the additional feature of being able to undercut hard packed snow and ice without resorting to steep side design and without imposing an unusual resistance to the impelling means for the plow. The downturned portion of the cutter bar tends to keep the nose of the plow in close relation to the surface of the road or in other words it holds the plow down without holding it back. At the same time this is so positioned to the angle of the mold board that no resistance is encountered by the upturned snow as it is moved 75 backward.

80 While such a cutter bar is of course subjected to unusual strains in meeting the resistance of the snow and the vertical strains of the compaction, we have provided for a 85 basis of unitary distribution of these strains through the combination of our cutter bar with the mold boards through a simple base frame construction which we have heretofore described. As before stated, this consists essentially of a V-shaped frame formed by the angle or V beams 7 which support the mold boards 1 at a point just in the rear of their cutting edge. Below this is the reinforcement bar 6 which is supported from the V- 90 beams 7 by the transverse webs 8 which are welded to each of said members into a box construction. These are again supported by the welded member 9 which constitutes the 95 cover or under-wear surface of the plow nose. 100

105 In operation the nose of such a plow will divide and laterally shift ordinary banks of snow in the usual way, but the lower portion of the nose of the V-shaped plow approaches so closely to a flat angle with the ground that it will lift or roll the snow instead of merely pushing and jamming it as is the case with the ordinary steep sided V shaped plow.

110 While approaching a flat angle with the ground by reason of which the nose penetrates the hard packed drifts, it has the tendency on account of its downturned edge to hold to the road level to undercut hard snow and ice and not pick up or ride as has been the 115 case with other plows with a low angle nose.

120 The forward edge of the cutter bars 5 at the juncture of the V-shaped portion of the plow is fitted with a member 17. This consists of a pair of plates or steel castings which conform in their cross section generally to that of the cutter bar. These are welded 125 at a common joint which is disposed in the line of the central weld 2. They include at their point of juncture a plate 18 which is 130

formed with a lower edge 18¹ which acts as a shoe or rider in case an obstruction is met such as a railroad crossing or other obstacle.

The cutter bars 5 are detachably bolted to

5 the reinforcing bar 6 so as to be removable or replaceable in case of wear or damage. As shown these bars are simple straight lengths and fit on to the bar 17 which constitutes a removable member also replaceable.

10 As before stated, the structure shown is a preferred structure in actual practice as one in which the parts combine to give very great strength and a very high efficiency. The cutter bars, however, may be given other 15 mounting and other backing and may be modified in forms within the limits of the claims directed thereto.

What we therefore claim and desire to secure by Letters Patent is:—

20 1. In a snow plow nose, a curved mold board having a low angle at its lower edge, and a cutter bar attached to said edge and having a portion in substantial continuation of the angle and having its lower margin 25 downwardly divergent therefrom to constitute a downwardly inclined cutting edge.

2. In a snow plow nose, a curved V shaped mold board having a low angle at its lower edges, and a cutter bar attached to each of 30 said edges and having portions in substantial continuation of curvature of the mold board but having their lower margins turned downwardly to constitute an inclined cutting edge.

35 3. A cutter bar for the curved mold board of a snow plow having a portion in substantial continuation of the curvature of the mold board and having its lower margin downwardly divergent therefrom to constitute a 40 downwardly inclined cutting edge.

4. A cutter bar for a snow plow having a portion in substantial continuation of the lifting angle of the plow and having its lower margin downwardly divergent there- 45 from to constitute an inclined cutting edge.

5. In a snow plow nose, a pair of V-shaped mold boards of concaved curvature, a cutter bar attached to each lower edge of each mold board and having portions in substantial continuation of the curvature of said mold 50 boards and terminating in downwardly inclined cutting edges whereby each cutter bar as a whole is in effect concaved in reverse direction to the curvature of the mold board to which it is attached.

55 6. In an snow plow nose, a pair of V-shaped mold boards of concaved curvature, a cutter bar attached to each lower edge of each mold board and having portions in substantial continuation of the curvature of said mold boards and terminating in downwardly inclined cutting edges whereby each cutter bar as a whole is in effect concaved in reverse 60 direction to the curvature of the mold board

to which it is attached, and reinforcing bars underlying said cutter bars.

In testimony whereof we affix our signatures.

GEORGE C. SOULE.
